UNITED STATES PATENT OFFICE.

FRANK B. CLENCH, OF LOCKPORT, NEW YORK.

DESIGN FOR A PHOTOGRAPHIC MOUNT OR CARD.

SPECIFICATION forming part of Design No. 13,465, dated December 5, 1882.

Application filed October 4, 1882. Term of patent 7 years.

To all whom it may concern:

Be it known that I, FRANK B. CLENCH, a citizen of the United States, residing at Lockport, in the county of Niagara and State of New York, have made, invented, and produced a new and original Design for Photographic Mounts or Cards, of which the following is a specification, reference being had to the accompanying drawing, forming part thereof.

10 The drawing or exhibit shows a card of the usual size on which photographic portraits are to be mounted, with my new design for ornamenting the same thereon, the object being to take off in certain pictures the bare look at the top and bottom of such "mounts" by putting at the left hand, at the top, and at the right hand, at the bottom, an ornamental engraved and printed design. Heretofore the photograph usually covered nearly all the surface of the 15 card, and outside of the picture is usually a flat tint, the result of the action of the printing on the sensitized paper. Especially is this the case in my new "plaque" pictures, patented October 10, 1882, No. 13,330, or those taken 20 as "vignettes," &c. To take off the effect of this dead surface is the object of this invention.

25 The leading features of my design consist in the engraved strips, printed in any color or colors, one at the top A of the card B and the other at C, near the bottom, leaving at the bottom the usual space for name, &c., of the artist. In the top strip the word "Plaque" is usually printed, made in ornamental letters,

and to be used on those cards made with the "plaque effect" of pictures, and with ornamental lines about it. At the left end the design is widened a little downward, as shown at c', and at the opposite end, a, a space, b, is left. The lower ornamental strip, C, is of a similar nature and effect as the strip A, except that it is widened at the right-hand side upward to the edge of the card, as at c', and a space, b', is left on the left-hand side, as shown. In the right-hand corner of the lower strip, where it is widened, as at c', is a circular ornamental 40 place, d, for the monogram of the artist to be printed or set therein, or for any particular ornamental effect desired or dictated by taste. So with the peculiar ornamentation of the strips A and C. 50

I claim—

The design for photographic mounts or cards herein shown and described, the same consisting of the card B, having the ornamental strips A and C thereon, both widened at one end, c and c', and leaving blank spaces b and b' on the card, and with the ornamental circle d, and with the word "Plaque" on the upper strip. 55

In witness whereof I have hereunto signed my name in the presence of two subscribing 60 witnesses.

FRANK B. CLENCH.
